UNITED STATES PATENT OFFICE.

HARRY J. BRINKMAN, OF DAYTON, OHIO.

TOY POOL TABLE.

Application filed June 20, 1927. Serial No. 199,943.

My invention relates to toy game tables, carom and crokinole boards and the like, and more particularly to such a toy table or board constructed from sheet metal. For illustrative purposes the invention is shown embodied in a toy pool table. While it is recognized that toy pool tables have heretofore been manufactured from sheet metal the operations of manufacture and assembly have been expensive and the resulting structures have not always been stable, rigid and durable.

In the present construction the sheet metal top of the table is braced and stiffened to prevent buckling by means of an inclined runway for balls which is attached to the under side of the table top in inwardly spaced relation with the marginal edges. The table is provided with sheet metal stamped legs at its corners, which are connected with the table top. They are provided with medially disposed spaced grooved recesses at different heights for the engagement of the ball runway in the uppermost of such grooved recesses at different heights for the engagement of the ball runway in the uppermost of such grooved recesses at one end of the table and in the lowermost of the recesses in the legs at the opposite end of the table. The table top is provided with a reversed upstanding marginal flange which is bowed outwardly to form bays coincident with the corner and side pockets or deposit openings for balls provided in the table top. The utilization of the ball runway which is formed from sheet material upwardly flanged at both its inner and outer margins connects the table top to the legs at different points and rigidly supports the central portion of the table top against vibration or buckling and affords upon the whole a strong durable and unyielding structure.

The object of the invention is to simplify the structure as well as the means and mode of assembly of toy pool and billiard tables and the like, whereby they will not only be cheapened in construction but will be more efficient in use, more rigid, sturdy and durable, capable of being economically constructed and unlikely to get out of repair.

A further object of the invention is to provide improved means for bracing and stiffening the sheet metal top of such table to eliminate vibration and buckling.

A further object of the invention is to pro-

vide an improved form of ball runway for returning balls deposited through the receiving openings or pockets.

A further object of the invention is to provide an improved form of supporting legs for such table and to provide means for interengaging the ball runway with such legs in spaced relation with the table top.

With the above primary and other incidental objects in view as will more fully appear in the specification the invention consists of the features of construction, the parts and combinations thereof, the mode of operation, or their equivalents, as herein-after described and set forth in the claims.

Referring to the accompanying drawing wherein is shown the preferred but obviously not necessarily the only form of embodiment of the invention, Fig. 1 is a perspective view of the assembled toy game table forming the subject matter hereof. Fig. 2 is a transverse sectional view on line 2—2 of Fig. 1. Fig. 3 is a sectional view upon a diagonal line 3—3 through the corner of the table and supporting leg. Fig. 4 is a bottom plan view illustrating the proportions and relation of the ball return way which also braces and stiffens the table top. Fig. 5 is a detail view showing a modification wherein the runway is disconnected from the legs. Fig. 6 is a sectional view on line 6—6 of Fig. 5.

Like parts are indicated by similar characters of reference throughout the several views.

Referring to the accompanying drawing, 1 is the top of the game table, which in the present instance is illustrated as a pool table. This top is formed from sheet material, preferably sheet metal, although fiber or composition may be used. The top 1 is provided with an upstanding marginal flange of substantially inverted U shape, which forms the rail of the pool or billiard table or carom board. The top 1 is provided with pocket openings 3 at the corners and also at mid-length points. The upstanding marginal flange or rail 2 of the top is bowed outwardly coincident with the holes or pockets 3 thus forming bays defining the outer margins of the holes or pockets. The top surface of the game table top is preferably, though not necessarily, covered with a felt layer in imitation of a regulation pool and billiard table.

The top 1 is supported at its corners by

legs 4. These legs are also formed from sheet material. They are of substantially channel shape or semi-circular and taper downwardly. Adjacent to the upper ends of the legs 4 are provided with laterally projecting wings 5 which extend in substantially right angle relation with each other. The top margins of the wings 5 and the upper end of the main leg portions 4 are seated within the recess formed by the inverted U shaped upstanding marginal flange 2 of the table top. The legs are secured to the top preferably by soldering or spot welding. However, other means of attachment may be employed. The supporting legs 4 of the table 1 are provided at mid-height points with horizontally disposed spaced concavo-convex beads or ribs 6. These beads or ribs 6 afford upon the interior of the channel shaped legs 4 spaced grooved depressions at different heights. The transverse beads or ribs 6 not only serve to stiffen and strengthen the supporting legs and give to them a massive appearance in simulation of the legs of a regulation pool or billiard table, but the interior spaced grooved recesses constitute sockets to receive the margins of the inclined ball race or runway located beneath the table top.

Sheet metal table tops such as the top 1 not braced or stiffened are quite subject to vibration and to buckling and do not afford the necessary rigid surface for proper play of the balls thereover. In the present instance there is provided beneath the table top 1 an inclined return way for balls deposited through the openings or pockets 3 which also has the additional function of bracing and stiffening the table top. This runway or receiver for deposited balls is also formed from sheet material.

The central portion of a sheet of material is removed and the margins of such central opening are upturned to substantially perpendicular relation with the plane of the sheet as shown at 8. This sub-structure forming the runway or return way for balls thus comprises a substantially rectangular frame having integral upstanding flanges 8 at its inner margins. These flanges are attached to the under side of the table top 1 on lines spaced inwardly from and substantially parallel with the margins thereof. The lateral gutter like portions 9 of such sub-structure are provided with upstanding marginal flanges 10 of substantially inverted U shape. The rectangular frame like sub-structure forming the runway or return way for balls is of substantially the same proportions as the table top 1. The upstanding innermost flanges 8 which are of much greater height than the outer marginal flanges 10 are tapered, or are of less height at one end than at the other, and are secured to the underside of the table top by

soldering, welding, brazing or similar means. The marginal flanges 10 of the sub-structure seat within the uppermost of the grooved recesses afforded by the concave beads or ribs 6 of the legs at one end of the table and at the opposite end of the table the marginal flanges 10 of the structure seat within the lowermost of such grooved recesses formed within the legs.

Thus the runway for balls is supported in an inclined relation with the table top and is firmly secured by being seated within such grooved recesses of the beads or ribs 6. The sub-structure or runway is not only secured to the underside of the table top but is also secured to the legs within such grooved recesses by being welded or soldered. Thus the central portion of the table top is connected to the supporting legs at mid-height points by such substructure or ball runway. The upstanding flanges of the runway being secured in both longitudinal and transverse positions relative to the table top 1 serve to rigidly support the top against vibration and buckling.

While the invention has been illustrated in the form of a toy pool table it is to be understood that it may be made with equal sides and with pockets or openings 3 at the corners only in which case it may be employed as a carom or crokinole board.

While the runway or gutters for receiving the balls are preferably connected directly with the supporting legs by being seated in the corrugations or grooved recesses 6 it is not at all essential that they be so connected. It is found in the manufacture that the support of the runway or gutters upon the under side of the table top is amply sufficient and that such runway or ball gutter may terminate in spaced relation with the supporting legs 4 as shown in Figs. 5 and 6. In these figures the runway is shown wholly detached from the legs which are sufficiently braced by the attachment of their wing portions 5 with the table top.

At one end of the table the runway or ball gutter is depressed as at 11 to collect the balls conveniently for removal. The depression of the gutter affords ample space between the table top and the runway for the insertion of the player's fingers. It is to be noted, however, that this collecting portion of the runway does not protrude beyond the table top but is contained wholly beneath such top. It is found that by making the gutters 9 of transversely arcuate form the runway is greatly strengthened and stiffened and the balls are returned more quickly and directly to the depressed end of the runway than if such runway was flat.

By omitting the holes or pockets 3 and providing strips of rubber or felt upon the

inner side of the upstanding marginal flanges 2, the same general structure may be employed for a billiard table.

- While the invention is illustrated as a toy pool table it is to be understood that it is not limited to such use but that the term "pool table" as herein employed is to be understood as including the features of a billiard table or a carom or crokinole board.
- 10 In the event that the pockets or openings are not employed the substructure performs the function of bracing and stiffening the table, without however, serving as a return way for balls.

15 While any sort of cue stick or impeller may be employed, a spring actuated cue such as disclosed in my co-pending application Serial No. 199,947 filed of even date herewith is preferably employed in propelling 20 marbles about the top 1 of the table in simulation of pool balls. In the event that the deposit holes or pocket 3 are not employed, such marbles may be employed as billiard balls.

25 From the above description it will be apparent that there is thus provided a device of the character described, possessing the particular features of advantage before enumerated as desirable, but which obviously is 30 susceptible of modification in its form, proportions, detail construction and arrangement of parts without departing from the principle involved or sacrificing any of its advantages.

35 While in order to comply with the statute the invention has been described in language more or less specific as to structural features, it is to be understood that the invention is not limited to the specific details shown, but 40 that the means and construction herein disclosed comprises the preferred form of several modes of putting the invention into effect, and the invention is therefore claimed in any of its forms or modifications within 45 the legitimate and valid scope of the appended claims.

Having thus described my invention, I claim

1. In a toy pool table, or the like, a table 50 top having pocket openings therein, supporting legs attached to said top having in their inner faces grooved recesses and an inclined runway for balls deposited through the pocket openings, engaged in the grooved recesses of said legs at different elevations 55 at opposite ends of the table.

2. In a toy pool table, or the like, a table top formed from sheet material, supporting legs connected to said top, and means engaged with the legs in spaced relation below the top and engaging the under side of the table top at points spaced inwardly from said legs for stiffening said sheet material top against buckling.

65 3. In a toy pool table, or the like, a table

top formed from sheet material and having pocket openings therein, supporting legs therefor, and a runway for balls deposited through the pocket openings attached to the under side of the sheet material table top 70 at points spaced inwardly from the margins thereof to stiffen said sheet material top against buckling.

4. In a toy pool table, or the like, a top 75 formed from sheet material and having pocket openings therein for the deposit of balls, supporting legs therefor, and substantially J shaped run ways for balls deposited through said openings, having their up-standing sides attached to the under side 80 of the sheet material table top in inwardly spaced relation with the margins thereof and having their lateral bottom portions attached to said supporting legs.

5. In a toy pool table, or the like, a table 85 top having pocket openings for the deposit of balls, supporting legs therefor, and runways for deposited balls comprising a rectangular frame formed from sheet material, the inner margins of the rectangular frame 90 being upturned and attached to the under side of the table top in inwardly spaced relation with the margins thereof.

6. In a toy pool table, or the like, a table top having pocket openings for the deposit of balls, supporting legs therefor, and runways for deposited balls comprising a section of sheet material having its central portion removed and a series of upturned 100 integral tongues formed contiguous to the open central portion and secured to the under side of the table top in inwardly spaced relation with the margins thereof.

7. A toy pool table, or the like, including 105 a table top formed from sheet material, an upstanding integral marginal flange bounding said table top, said top having pocket openings therein at spaced intervals and contiguous to said integral marginal flange, said flange being deflected outwardly coincident with said openings, and supporting legs for said table top.

8. A top for a toy pool table comprising 115 a single piece of sheet material formed into a substantially rectangular pan like structure, and having holes at spaced intervals, the upstanding sides of the pan like structure being projected outwardly to form arcuate bays defining the outer margins of said holes.

9. A leg for a toy pool table formed from sheet material and comprising a substantially channel shaped body having at mid-height points spaced substantially horizontally disposed grooved recesses in the inner 125 face of the channel shaped body.

10. In a toy pool table, or the like, a table top formed from sheet material and having an integral upstanding reversed marginal flange, forming a substantially rectangular 130

pan like structure and having holes at its corners, the marginal flange being extended in arcuate bays enclosing the holes at the corners of the top, and supporting legs formed from sheet material of substantially semi-circular cross sectional form agreeing with such extended arcuate corner bays and engaged beneath the reversed portion of the upstanding marginal flange, coincident with 10 said bays.

11. A leg for a toy table, or the like comprising a substantially channel shaped body formed from sheet material, lateral wing portions projecting therefrom in substantially 15 right angle relation to each other, said channel shaped body being transversely corrugated at a midlength point.

12. A toy pool table comprising a top formed from sheet material having an upstanding integral marginal flange and having holes contiguous to said flange for the deposit of balls, the flange being deflected outwardly about said holes, channel shaped supporting legs formed from sheet material 20 located at the corners of said top and engaged with the upstanding marginal flanges thereof, said legs being transversely recessed at different heights, and runways for deposited balls secured to the under side of the 25 sheet material top to stiffen same against buckling, and also having engagement in the transverse recesses at different heights in the supporting legs at opposite ends of the table to support the runways in inclined position 30 beneath the table top.

13. In a toy pool table, or the like, a table top formed from sheet metal having an integral upstanding reversed marginal flange forming a substantially rectangular pan like 40 structure and having openings therein at spaced intervals, supporting legs attached to said table top, and a rectangular frame like runway for balls deposited through the openings located in inclined spaced relation 45 beneath the table top and attached to the under side thereof in spaced relation with the margins of the table to stiffen said sheet metal top.

14. In a toy pool table, or the like, a table 50 top formed from sheet metal having an integral upstanding reversed marginal flange forming a substantially rectangular pan like structure and having openings therein at

spaced intervals, supporting legs attached to said table top, and an inclined runway for 55 balls deposited through the openings extending in parallel relation adjacent to opposite sides of the table and transversely across one end thereof, said transverse portion of the runway being medially depressed to facilitate removal of the balls but contained wholly beneath the table top.

15. In a toy pool table, a table top having marginal flanges and spaced openings through which balls are deposited, supporting legs for said top and an inclined runway located beneath said top to receive the balls and direct same toward one end of the table, said runway having therein a depression at its lower end in which the balls are collected, 60 said runway including said depressed ball collecting portion being confined entirely beneath the table top.

16. In a toy pool table, a table top having marginal flanges and spaced openings 75 through which balls are deposited, supporting legs for said top, and inclined gutters of arcuate transverse contour located beneath the said table top and at the inner sides of said legs to receive balls deposited through 80 the openings.

17. In a toy pool table, a table top having marginal flanges and spaced openings through which balls are deposited, supporting legs for said top, and inclined gutters of arcuate 85 transverse contour located beneath the said table top and at the inner sides of said legs to receive balls deposited through the openings, said gutters being attached to said legs in spaced relation with the table top and also 90 attached to the under side of the table top in inwardly spaced relation with the margins thereof to stiffen said top.

18. A runway for a toy pool table comprising parallel transversely interconnected 95 gutters of arcuate transverse contour forming a substantially rectangular frame like structure and outwardly extending arcuate bays formed at the ends and intermediate points of said gutters for registry with deposit openings in the top of a table with which the runway is to be employed.

In testimony whereof, I have hereunto set my hand this 21st day of May, A. D. 1927.

HARRY J. BRINKMAN.
